AUDLEY E. HARNSBERGER AND CLYDE L. SMITH, OF CHICAGO, ILLINOIS, ASSIGNEES
TO GYRO PROCESS COMPANY, OF DETROIT, MICHIGAN, A CORPORATION OF MICHIGAN

APPARATUS FOR CRACKING HYDROCARBON OILS

Application filed October 30, 1929. Serial No. 403,583.

This invention relates to the art of cracking mineral oils and, more specifically, to the production of oils of relatively low boiling point from oils of higher boiling points, and 5 wherein molecular decomposition of such higher boiling point oils takes place while the oils undergoing decomposition are in the vapor phase.

It is a primary object of the invention to 10 provide a vapor phase system of cracking oil wherein is recovered a larger percentage of the desired end point distillate, usually motor fuel, than has been obtained through the operation of previous systems of this 15 character, and in obtaining this advantage the invention has for ancillary objects to minimize, during the cracking of the oils, the formation of fixed gas and heavy residual oils.

20 A further object of the invention resides in providing for improved heat transmission to the vaporized oils undergoing molecular decomposition wherein said oils are heated in a uniform manner throughout substantially 25 the entire body thereof and in such a manner as to avoid overheating of certain portions of the oil and underheating of other portions thereof. It has been found that there are certain optimum temperatures in the cracking 30 of oil in the vapor phase which provide for the most efficient operation, and the present invention provides for the passage of the oil vapors through the converter in such manner as to secure the transmission of 35 these optimum temperatures to the oil vapor and to permit these temperatures to be maintained practically and relatively throughout the duration of the cracking operation.

For a further understanding of the invention 40 reference is to be had to the following description and the accompanying drawing wherein:

Figure 1 is a diagrammatic view illustrating conventional apparatus employed in carrying out the present invention,

Figure 2 is a vertical sectional view taken through the converter, and

Figure 3 is a transverse vertical sectional view taken through the converter.

50 Referring more particularly to the draw-

ing, the numeral 1 designates a vaporizing furnace which in practice partakes of the form of a pipe still and oil enters the vaporizing furnace by way of the pipe line 2 and is continuously forced by a pump 3 through the line 2 and the heating coil 4 arranged within the furnace 1. The internal temperature of the furnace is regulated so that the oil passing through the coil will be subjected to vaporizing temperatures but which temperatures will be below temperatures which would be apt to produce material cracking of the oil. From the coil 4 the oil is passed into an evaporator 5 where, due to the decreased pressure, a separation of the vaporous constituents of the oil takes place from the heavy liquid constituents. These liquid constituents collect in the bottom of the evaporator 5 and may be withdrawn from the system by the pipe 6.

Leading overhead from the evaporator 5 is a pipe line 7 through which the vaporized fractions of the oil released from the evaporator are passed. These vapors are employed as the cracking stock and it has been found desirable, for purpose of minimizing carbon and coke deposit, to eliminate liquid entrainment in the vapors flowing from the evaporator to the cracking zone of the converter 8. In removing such liquid fractions or particles, the line 7 is equipped with a separator or liquid trap 9 which functions to eject liquid entrainment from the vaporized oils. The vapor outlet line 10 which leads from the separator to the converter terminates in coils 11, the individual pipes of which possess an appreciable cross-sectional area to prevent high velocities of vapor flow through the coil.

The converter 8 comprises a furnace formed to include a setting 12 in which is located a bridge wall 13 serving to divide the interior of the setting into combustion and tube chambers 14 and 15 respectively. The combustion chamber is provided with a burner 16 of sufficient capacity to develop the required converting temperatures within the setting. The heated gases pass from the top of the combustion chamber 14 over the bridge wall 13 and sweep downwardly through the heating coils located in the tube chamber 15. The

- furnace gases released from the lower or cooler portion of the tube chamber may then be passed to the vaporizing furnace 1 for use in heating the oil passing through the coil 4.
- 5 It will be noticed that the coil 11 is situated in the zone of lower temperature of the tube chamber 15 and sufficient heat ordinarily is absorbed by the oil vapors flowing through the coil 11 to raise the temperature of the oil 10 from, for example, 700° F. to 750° F. The pipes comprising the coil 11 serve, therefore, as drying tubes in order to completely reduce to dry or vaporized form the oil stock prior to its introduction into the main zone of conversion.
- The outlet side of the coil 11 is connected with a pipe line 17 which leads to a manifold or header 18 arranged adjacent to the upper part of the converter. Connected with this 20 header are parallel horizontally extending converter tubes 19. These tubes are of smaller diameter or cross-sectional area than the tubes comprising the coil 11 and the pipe line 17. The tubes 19 are disposed in the upper 25 portion of the converter setting and are positioned over the combustion and tube chambers 14 and 15. The entrance portions of the tubes 19 are thus disposed immediately over the combustion chamber 14 in order to receive radiant heat developed through the 30 combustion of fuels in the chamber 14 and to permit the radiant heat employed to be utilized effectively in securing a rapid rise in the temperature of the oil vapors from an 35 entering temperature of approximately 750° F. to temperatures in excess of 1000° F. In fact, the oil vapors discharged from the rear ends of the tubes 19 possess a temperature of approximately 1100° F. to 1120° F., although 40 these temperatures may vary between 1000° F. and 1150° F. Therefore, due to the small cross-sectional area of the tubes 19 and the consequent high velocity of vapor flow therethrough and, furthermore, due to the location 45 of the tubes 19 in the converter setting, a construction is provided permitting of rapid and effective heat transfer between the oil vapors and the surrounding heating medium and by this arrangement the oil vapors 50 are brought rapidly to a desired converting temperature with minimum deposition of coke or carbon or gas formation.

In order to secure the necessary time element to effect thorough conversion of the oil 55 stock during its passage through the converter and yet to prevent overheating, on one hand and underheating on the other, the tubes 19 enter, at their discharge ends, into a second header 20 arranged parallel to the first header 18 and on the opposite side of the converter setting. The header 20 is connected by a pipe 21 of relatively large diameter, as regards the pipe 17, and leads to a bank of large size converting tubes 22, which are arranged 60 in the tube chamber 15 above the coil 11.

Preferably, the flow of oil vapor undergoing conversion through the tubes 22 is countercurrent to the flow of the furnace gases and this arrangement provides for a substantially uniform maintenance of converting temperature 70 on the part of the oil vapors without material fluctuation. Due to the large cross-sectional area of the tubes 22, the velocity of vapor flow therethrough will be lower than that which obtains in the smaller parallel tubes 75 comprising the first converter pass 19. It will be observed that the flow of the vapor through the tubes 19 may be termed a "multi-stream" or parallel flow, whereas in the final conversion zone the flow takes place through the tubes 22 in series form, that is, progressively through the several tubes comprising the coil bank 22.

Converted vapors released from the bank 22 pass by way of a line 23 into a conversion 8 arrester 24, and when the vapors enter the arrester they may possess a temperature varying between 1000° F. to 1150° F. In the arrester the vapors are brought into direct physical contact with sufficient quantities of liquid cooling oil to secure an almost instantaneous reduction in the temperature of the oil vapor from conversion temperatures in excess of 1000° F. to non-reacting temperatures not in excess of 600° F. Cooled oil is sprayed into the arrester from a pipe line 25 which leads to a source of oil supply 26 wherein is contained the charging stock. The oil vapors released from the arrester pass into a fractionating tower 27 where the end point of the overhead vapors may be readily controlled. The vapors released from the top of the tower 27 may then be condensed as at 28 and led to a storage tank 29. The liquid which collects in the bottom of the arrester 24 is passed to the bottom of the fractionating tower by way of the line 30, and the line 2 is connected with the bottom of the fractionating tower to force this liquid, which constitutes a charging stock, through the vaporizing furnace, wherein the cycle of operation above given is repeated.

Having thus described the invention, the distinctive features thereof may be summarized as follows:

First, the taking of a body of oil vapors and thoroughly drying the same by passage through a tube coil (11) located in a portion of the converting furnace where the heating medium is within 400° F. or 500° F. of the temperature of the oil vapor at the time the vapor enters the tube coil, thereby insuring a mild condition of low furnace temperatures on the drying tubes even though the latter should become partially filled with coke or carbon due to the drying process. Since the tubes comprising the coil 11 are of large area the formation of coke on the walls thereof does not interfere with sustained operation of the converter since, due to the provision

5 of the evaporator 5 and the trap 9, but small quantities of liquid reach the drying tubes and then, due to the cross-sectional area of such tubes, the carbon deposit therein does not attain a thickness sufficient to interfere materially with the oil vapor flow through the tubes for effecting heat transfer between the oil vapor and the internal heating medium.

10 Second, the invention provides for the dividing of the single dry stream of oil vapor into a number of parallel or multiple smaller streams, which is accomplished by the provision of the header 18 and the converting tubes 19. Within these latter tubes the ratio 15 of surface-to-volume is increased in order to effect rapid heating of these dry vapors to a cracking temperature, which is accomplished by exposing these multi-streams of oil vapor to a high degree of radiant heat and this is 20 accomplished without permitting any one stream to crack beyond a point of maximum efficiency and we preferably limit the cracking in the tubes 19 to less than 25 per cent of the total cracking performed in the converter.

Third, by recombining these multi-vapor streams into one stream by the employment of the pipe 21, we thereby bring about a condition where the entire mass of the vapor is 30 brought to the same temperature, although for various reasons the temperature of the oils in passing through the different tubes 19 may vary in one tube with respect to the others. The recombined stream of oil vapor is then exposed to a moderate degree of radiant and convection heat in the furnace setting, and the location of the coil 22 in said setting is such as to permit of the supplying 40 to the oil vapor of that quantity of heat made necessary by the endothermic conversion reactions, and at the same time holding the vapors at this point at substantially a constant temperature.

45 The advantages of the above construction and system of operation are many. In operation, in the case of a 1000 barrel converter the vapors normally enter the 10 inch drying tubes 11 located in the base of the converter, the entering temperature of the vapor being 50 approximately 700° F. and the exit temperature 740° F. to 750° F. These vapors are then conducted to the front of the converter over the fire box zone and split into approximately 55 60 small streams comprising the tubes 19. At the end of this top row of tubes the header 20 is provided which conducts the vapors into the single pipe line 21 of approximately 60 12 inches in diameter, and from the pipe line 21 the oil vapors pass through 65 the bank of tubes 22 also composed of 10 inch tubes and which are so arranged in the furnace setting as to maintain the converting temperature of the oil vapors.

65 In prior systems the small tubes are con-

tinued in the tube chamber with the result that the vapor flows in a plurality of streams of small cross-sectional area through the entire converter, just as we provide for the first pass of the converter. It is our thought that the reason such prior systems do not obtain 70 high conversions and consequent high gasoline yields is that the degree of cracking in each of these multiple streams vary somewhat being too great in certain streams or passes 75 and insufficient in others, and that, therefore, the results obtained are a composite of under-cracking and over-cracking. It has been observed that with such prior systems which operate at high temperatures in order 80 to crack hard enough to secure high gasoline yields, there results in considerable over-cracking on some of the vapor streams, which produces too large quantities of fixed gas to make such an operation economically feasible 85 and, conversely, if the temperatures are too low the gasoline yield falls and the per cent- age of recovery of gasoline is too low for economical operation. Thus, to overcome 90 these conditions the present invention resides 95 in recombining the multiple streams after their passage through the first portion of the converter into a single stream, wherein a uniform heating of all portions of the oil vapor takes place.

The reason that one large tube is not used 100 throughout the converter is attributable to the fact that such a tube in order to secure sufficient heating surface would have to be very long, and further, in order to secure heat transfer, would require a high vapor velocity 105 which would result in detrimentally high frictional back pressures. By dividing the vapor stream into a large number of small streams for passage through the high radiant heat zone the surface-to-volume ratio is very greatly increased. For instance, one 12 inch pipe is equivalent to 16 three inch pipes in cross-sectional area and with a given vapor flow either would have the same vapor velocity. However 16 three inch pipes have approximately 12½ square feet of heating surface 110 available per foot of length or four times as much heating surface as one 12 inch pipe, which has only three and one-half square feet of heating surface per linear foot. However, at the end of the first pass 19 the converter is operated so that the vapor temperature may be approximately 1100° F. and, therefore, since most of the heating is done 115 120 we are then permitted to recombine the multi-streams into one large stream and without difficulty secure a sufficient heating surface to supply the loss of heat due to the endothermic cracking reaction, and yet limit the exposure 125 of the oil vapors to said converting tempera- tures for the proper period of time necessary to secure the most efficient results.

What is claimed is:

1. An oil converter comprising an enclos- 130

- ing wall structure, a vertical bridge extending transversely of said wall structure and dividing the latter internally into combustion and tube chambers, said chambers communicating relatively over said bridge wall, a row 5 of horizontally extending parallel tubes supported by said wall structure and disposed openly in the upper portion of said converter over said combustion and tube chambers and 10 providing for parallel flow of oil vapor in a multiplicity of similarly moving adjacent streams, a header connected with the entrance ends of said tubes, a bank of serially connected tubes disposed in said tube chamber 15 and connected with the discharge ends of said parallel tubes, said serially connected tubes possessing a greater cross sectional area than any one of said first-named parallel tubes, combustion developing means situated in 20 said combustion chamber for producing furnace temperatures within said converter sufficiently high to heat oil vapors passing through said tubes to desired conversion temperatures, and a third bank of tubes disposed 25 in the low-temperature zone of said tube chamber, the discharge side of said third bank of tubes being connected with said header.
2. An oil converter comprising a refractory wall structure, a bridge disposed within said wall structure and extending transversely thereof to divide the interior of the converter into combustion and tube chambers, said chambers communicating over the top of said bridge, combustion developing means disposed 30 in said combustion chamber, a plurality of horizontally arranged parallel tubes supported by said wall structure in the upper portion of the converter and extending openly over said combustion and tube chambers 35 said tubes providing for parallel flow of oil vapor therethrough in a multiplicity of similarly moving adjacent streams, a header disposed exteriorly of said wall structure and connected with the vapor inlet ends of said tubes, a plurality of serially connected tubes arranged in 40 said tube chamber immediately below said parallel tubes, connections between the discharge ends of said parallel tubes and said serially connected tubes, said serially connected tubes possessing a greater cross sectional area than the individual parallel tubes, a plurality of drying tubes disposed in said tube chamber below 45 said serially connected tubes, means for delivering substantially vaporized oils to said drying tubes, pipe means connecting the discharge side of said drying tubes with said header, said combustion developing means serving to heat and maintain the vaporized oils passing through the parallel and serially connected tubes at temperatures in excess of 50 1000° F. and to heat the vapors passing through the drying tubes to a non-cracking temperature sufficiently high to eliminate liquid entrainment in such vapors.
